Attorneys.

UNITED STATES PATENT OFFICE.

HUGH A. PERRY, OF CHICAGO, ILLINOIS.

SPIKE FASTENER.

Application filed August 4, 1921. Serial No. 489,787.

To all whom it may concern:

Be it known that I, HUGH A. PERRY, a subject of the King of England, residing at Chicago, in the county of Cook and State 5 of Illinois, have invented new and useful Improvements in Spike Fasteners, of which the following is a specification.

This invention relates to anti-slipping devices for shoes, and its object is to provide 10 a simple and efficient construction of spikes for use in connection with sport shoes and particularly those used in connection with running, baseball and football shoes and the like, and more particularly to provide an 15 improved means for securing or positioning the spike upon the shoe sole so as to prevent the displacement or detachment of the same or the mutilation of the sole by reason of strains applied thereto; and with this object in view the invention consists in a construction and combination of parts shown 20 in the accompanying drawing, wherein:—

Figure 1 is a perspective view of a shoe sole inverted having spikes embodying the 25 invention applied in the operative position thereto; Fig. 2 is a sectional view of the spike and shoe sole engaged thereby, the spike being shown partly secured; Fig. 3 is a view similar to Fig. 2 showing the spike 30 completely secured, and Figs. 4 and 5 are sectional views showing modifications.

Referring specifically to the drawing, the spike consists of a base or shank portion 10 extended to form the spike stem 11 which is 35 pointed as illustrated but may be of any desired form, the said shank being provided with a head 12 consisting of a disk adapted to come in contact with the inner surface of the shoe sole 13. In connection 40 with the spike shank and as a means for holding the spike in place on the sole with the head 12 in tight bearing contact with the inner surface thereof, there is employed an eyelet 14 which is embedded in the sole 13, 45 and has its outer end flanged as shown at 15, said flange bearing against the outer surface of the sole. The flange 15 is therefore on one side of the sole, whereas the head 12 is on the opposite side.

50 The eyelet 14 is preferably driven or hammered into the shoe sole 13 so as to be embedded therein, and to engage its flange 15 with the exterior surface of the sole.

In the construction illustrated in Figures

2 and 3 the eyelet 14 is interiorly threaded, 55 and the shank 10 of the spike is threaded externally for engagement therewith, so that when the parts are united there is a definite interlocking relation between the shank and the eyelet, and the portion of the shoe sole 60 13 disposed within the area of the spike head 12 and the outstanding flange 15 is compressed or clamped there between.

A further means for securing the spike consists in forming the same with a shoulder 65 16, which latter, after the parts are assembled as shown in Fig. 2, is expanded by a suitable tool and forced outwardly to seat on the flange 15, as shown in Fig. 3. This expedient firmly clinches the spike and prevents all looseness.

In the construction illustrated in Fig. 4 the screw-threaded connection is dispensed with, and the shank 10^a is given a slight 70 taper, so that it is forced into the eyelet 75 14 by heavy pressure to obtain a frictional engagement therewith.

Fig. 5 illustrates another embodiment of the invention. Here the flanged eyelet 14 is left off, and the shoulder 16 is upset to 80 bear directly on the outer surface of a washer 17 interposed between the sole 13 and the shoulder, the sole being thus firmly clamped between the washer 17 and the spike 85 head 12.

It will be noted in each form of the device the engagement is with the body of the shoe sole, with the interposed portion of the sole clamped or compressed throughout a sufficiently large area around the spike to afford a substantial support for the spike and resist the transverse strains applied thereto notwithstanding the relative length of the projecting portions of the spikes.

I claim:

1. An anti-slipping device for shoes comprising a spike having a head at one end, an eyelet in which the headed end of the spike seats, said eyelet having an outstanding end flange which is spaced from the spike head, and means for securing the headed end of the spike in the eyelet, said spike also having a shoulder to engage the outside of the aforesaid flange.

2. An anti-slipping device for shoes comprising a spike having an outstanding flange at one end and threaded at said end, and an eyelet which is interiorly threaded to re-

ceive the threaded end of the spike, said eyelet having a flange at one end and its other end being opposite the spike head.

3. An anti-slipping device for shoes comprising a spike having an outstanding flange at one end and threaded at said end, and an eyelet which is interiorly threaded to re-

ceive the threaded end of the spike, said eyelet having a flange at one end and its other end being opposite the spike head, and the spike having a shoulder to engage the flange of the eyelet.

In testimony whereof I affix my signature.

HUGH A. PERRY.
